US0D1113481S

(12) **United States Design Patent** (10) Patent No.: **US D1,113,481 S**
(45) Date of Patent: ** Feb. 17, 2026

(54) **THERMOSTAT DEVICE WITH MOUNTING PLATES**

(71) Applicant: **DiversiTech Corporation**, Duluth, GA (US)

(72) Inventors: **Waseem Amer**, Islamabad (PK); **Anees Ahmed Jarral**, Islamabad (PK); **Muhammad Zeeshan Ashraf**, Islamabad (PK); **Umair Nawaz Khan**, Punjab (PK); **Aftab Farooqi**, Redmond, WA (US)

(73) Assignee: **DiversiTech Corporation**, Duluth, GA (US)

(**) Term: **15 Years**

(21) Appl. No.: **29/972,797**

(22) Filed: **Nov. 12, 2024**

Related U.S. Application Data

(63) Continuation of application No. 29/862,247, filed on Dec. 7, 2022, now Pat. No. Des. 1,055,713, which is a continuation of application No. 29/862,232, filed on Dec. 7, 2022, now Pat. No. Des. 1,055,720, which is a continuation of application No. 29/861,731, filed on Dec. 1, 2022, now Pat. No. Des. 1,055,719, which is a continuation of application No. 29/857,492, filed on Oct. 21, 2022, now Pat. No. Des. 1,027,677.

(57) **CLAIM**

The ornamental design for a thermostat device with mounting plates as shown and described.

DESCRIPTION

FIG. 1 is a perspective view of the thermostat device with mounting plates.

FIG. 2 is an exploded perspective view of the thermostat device with mounting plates, showing a back plate and a wall trim plate.

FIG. 3 is a front elevation view of the thermostat device with mounting plates.

FIG. 4 is a rear elevation view of the thermostat device with mounting plates.

FIG. 5 is a top plan view of the thermostat device with mounting plates.

FIG. 6 is a bottom plan view of the thermostat device with mounting plates.

FIG. 7 is a left side elevation view of the thermostat device with mounting plates; and,

FIG. 8 is a right side elevation view of the thermostat device with mounting plates.

The broken lines are included for the purpose of illustrating portions of the thermostat device with mounting plates and form no part of the claimed design.

1 Claim, 4 Drawing Sheets
